UNITED STATES PATENT OFFICE.

ALBERT A. MILLER, OF WELLSBURG, WEST VIRGINIA, ASSIGNOR TO EAGLE MANUFACTURING COMPANY, OF WELLSBURG, WEST VIRGINIA, A CORPORATION OF WEST VIRGINIA.

CONTAINER.

Application filed September 30, 1921. Serial No. 504,312.

To all whom it may concern:

Be it known that I, ALBERT A. MILLER, a citizen of the United States, residing at Wellsburg, in the county of Brooke and State of West Virginia, have invented a new and useful Improvement in Containers, of which the following is a full, clear, and exact description.

The present invention relates broadly to containers, and more particularly to dispensing containers, such as oil cans and the like.

Heretofore various forms of oil cans have been constructed to permit the discharge of oil upwardly therefrom, as required for lubricating purposes. Such oil cans have, however, either required a complicated arrangement of valves the operation of which was manually controlled, an arrangement dependent upon the production of a vacuum for operation, or a separate cylinder and manually operated plunger extending diagonally through the oil can and having an inlet aperture so positioned that when the can became partially emptied the force feed was ineffective. Such constructions are not only inefficient, but they are expensive.

The present invention has for its object the provision of a simple, inexpensive, and efficient container overcoming the objections raised to containers of the type referred to at present in use, and capable of discharging its contents upwardly, downwardly, or in any direction intermediate these two extremes, until the container is almost entirely emptied.

A preferred embodiment of the present invention is illustrated in the accompanying drawings, in which—

Figure 1 is a vertical sectional view through an oil can constructed in accordance with the present invention;

Figure 2 is a perspective view of the partition;

Figures 3 and 4 are detail views of one form of valve for the discharge spout;

Figure 5 is a top plan view of one of the valves for the partition; and

Figure 6 is a detail view of a modified form of valve construction for the discharge spout.

In the drawings there is illustrated an oil can comprising a main body portion 2 having a discharge spout 3 secured in any desired manner to the detachable cap 4. Form-

ing part of the discharge spout, is a sleeve 5 carried by the cap 4 in alignment with the upper portion of the spout and projecting downwardly into the main body of the can.

Adjacent its bottom edge, the body portion 2 may be suitably enlarged, as by stamping or spinning, to form a shoulder 6 and a downwardly extending outwardly flanged portion 7. Secured within the main body of the oil can and engaging the outwardly flanged portion 7 thereof and the shoulder 6, is a downwardly flanged partition 8. Extending upwardly from the partition and suitably secured thereto is a second sleeve 9 adapted to slidably engage the sleeve 5 projecting downwardly from the cap.

A bottom 10 having a peripheral shoulder 11 and flange 12 is then placed in position within the partition member and the bottom of the oil can and secured in this position by bending a portion of its flange 12 upwardly to form a seam. By reason of this construction, the bottom 10 forms a closure for the auxiliary chamber 13 and the bottom of the can body at a single operation. It will be apparent that the bottom is resilient or flexible to permit the same to be pushed inwardly a slight distance, as is customary in constructions of this general character.

The partition 8 is preferably provided with a central aperture receiving the sleeve 9, and within this sleeve may be secured a cage 14 provided with a check valve 15 of suitable construction controlling the passage of fluid from the auxiliary chamber 13 into the discharge spout 3. If desired, the cage 14 may be eliminated, and the sleeve 9 provided with a transverse pin 16, as illustrated in Figure 6, and the lower portion of the sleeve may be provided with an inwardly extending flange 17 to form a seat for the valve 15. Also formed in the partition 8 is one or more openings 18, which opening or openings may be located at any desired position. Working loosely in each opening so provided, is a valve 19 of such length that it abuts against the bottom 10 before it is freed from the opening, and preferably having a head 20 thereon sealing the opening when in one position and preventing the valve from falling into the interior of the body. According to a preferred form of the present invention, each of these

valves may be constructed of cork, or other light material, adapted to float from the full-line position indicated in Figure 1 to the dotted-line position when the oil in the auxiliary chamber 13 reaches a predetermined level, to seal the opening or openings 18. With such a construction, a predetermined amount of oil may always be maintained within the auxiliary chamber 13, and this chamber sealed from communication with the interior of the can, whereby movement of the bottom 10 inwardly will result in discharging some of the oil past the valve 15 into the spout 3, and consequently to the mechanism being lubricated. This construction provides a simple and inexpensive dispensing device which is effective for discharging the contents of the can upwardly through the spout as long as there is sufficient liquid within the can to hold the valves 19 in such position that they seal communication between the auxiliary chamber 13 and the interior of the can.

When it is desired to use the can in the normal way, that is, with the spout downwardly, the can is first moved to a substantially upright position to permit oil to flow from the interior thereof into the auxiliary chamber 13, and is then inverted and the bottom operated in the usual manner until the auxiliary chamber 13 is dry. Thereafter, the can is moved to its upright position and the operation repeated as found necessary. By positioning the opening or openings 18 adjacent the edge of the partition 8, it will be apparent that oil commences to flow from the interior of the can into the auxiliary chamber 13 upon a very slight tilting movement of the can from its fully inverted position.

The advantages of the present invention arise from a construction permitting the contents to be discharged either upwardly, downwardly, or at any desired angle by operating the can in the usual way; and it

will be apparent that any modifications in the construction of the various parts for effecting this operation may be made within the scope of the appended claims without departing from the spirit of the invention.

I claim:

1. A container of the character described, comprising a main body portion having a discharge spout and a bottom portion capable of movement for discharging the contents from the container through the spout, a ported partition within said body forming a chamber between said partition and the bottom, said spout being in communication with said chamber and a buoyant valve cooperating with the port in said partition, substantially as described.

2. A container of the character described, comprising a main body portion having a discharge spout and a bottom portion capable of movement for discharging the contents from the container through said spout, a partition within said body forming a chamber between said partition and the bottom, and buoyant means for maintaining a constant level of fluid in said chamber when the container is in upright position, substantially as described.

3. A container of the character described, comprising a main body portion having a discharge spout and a bottom portion capable of movement for discharging the contents from the container through said spout, a partition within said body forming a chamber between said partition and the bottom, and float valves controlling the passage of fluid from said body portion to said chamber for maintaining a constant level of liquid therein when the container is in upright position, substantially as described.

In testimony whereof I have hereunto set my hand.

ALBERT A. MILLER.
